(57) **CLAIM**

The ornamental design for a shoulder strap for bag as shown and described.

DESCRIPTION

FIG. 1 is a perspective view of a shoulder strap for bag showing my new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a cross-sectional view taken along lines 8-8 of FIG. 2 thereof;

FIG. 9 is a cross-sectional view taken along lines 9-9 of FIG. 2 thereof;

FIG. 10 is a cross-sectional view taken along lines 10-10 of FIG. 6 thereof; and,

FIG. 11 is a cross-sectional view taken along lines 11-11 of FIG. 6 thereof.

The broken lines illustrate portions of a shoulder strap for bag which form no part of the claimed design.

1 Claim, 9 Drawing Sheets
